UNITED STATES PATENT OFFICE.

WILLARD R. GREEN, OF CHICAGO, ILLINOIS, ASSIGNOR, BY MESNE ASSIGNMENTS, TO WALLACE NOVELTY COMPANY, OF NEW YORK, N. Y., A CORPORATION OF NEW YORK.

LAMP-SHADE.

1,117,131.

Specification of Letters Patent. Patented Nov. 10, 1914.

Application filed February 11, 1914. Serial No. 817,985.

To all whom it may concern:

Be it known that I, WILLARD R. GREEN, a citizen of the United States, residing in the city of Chicago, county of Cook, and State of Illinois, have invented new and useful Improvements in Lamp-Shades, of which the following is a specification.

This invention relates to shades for incandescent lights, and relates particularly to means to support the shade upon an incandescent lamp or bulb to have adjustment about the longitudinal axis of the lamp and to permit the shade to be adjusted to any desired angular position relative to the longitudinal axis of the lamp, and to provide a shade that is simple and cheap in construction, efficient in operation, and which can be readily placed upon and removed from the lamp. With this object in view I provide a pair of connected loops, the loops being at an angle to the connecting portion with the shade proper connected to said connecting portion, and the loops adapted to engage the bulb at opposite sides. The shade support is preferably made of a resilient yielding material, such as wire, with the loops in the form of a coil of a spiral spring with the connecting portion formed with an eye for the insertion of a screw or rivet to connect the shade proper thereto.

In the drawing accompanying and forming a part of this specification, Figure 1 is a side elevation of an incandescent electric light bulb with an embodiment of my improved shade applied thereto. Fig. 2 is a view looking at the end of an electric lamp bulb with my improved shade applied thereto and adjusted to a position at right angles to the longitudinal axis of the lamp. Fig. 3 is a perspective view of the shade looking at the bottom; and Fig. 4 is a sectional detail view to illustrate the manner of connecting the support to the shade.

Similar characters of reference designate like parts throughout the different views of the drawing.

My improved shade is particularly adapted for use in connection with incandescent electric lamp bulbs connected to a portable stand in which the lamp may stand in a perpendicular position or at any desired angle to the perpendicular, and in Fig. 1, I have shown in full lines my improved shade applied to such a lamp when in a perpendicular position to extend over the

top of the lamp and deflect the light rays downward.

The embodiment of my invention illustrated consists of a shade proper or deflector 6, in the present instance dome or semi-circular in shape. In the position illustrated the bottom of the shade is at right angles to the longitudinal axis of the lamp, and as stated it may be adjusted to any desired angle to and about the longitudinal axis of the lamp. For this purpose I provide a support for the shade consisting of a pair of loops 7, 8 to engage at opposite sides of the lamp so that a bulbed portion of the lamp projects through loops, the loops being at an angle to and integral with a connecting portion, as at 9, and by means of which it is connected to the shade proper or deflector. These loops are constructed of a suitable yielding or resilient material, preferably of spring wire, and are in the nature of a coil of a spiral spring, and while only a single coil is shown one or more coils may be used. Should only a single coil be used the ends of the coil overlap and such ends spaced apart from the adjacent wire strand, as clearly shown at 10 and 11 in Fig. 3, and such ends are adapted to lie adjacent the bulb as shown in Figs. 1 and 2. The connecting portion 9 of the loops is provided substantially midway thereof with an eye 12 for the engagement of a screw 13 to secure the shade supporting loops to the shade, said screw passing through an opening in the shade and having screw threaded connection with the nut 14 on the outside of the shade, this nut being of ornamental shape to enhance the appearance of the shade. The shade is clamped at the edges of the opening between the eye formed in the connecting portion of the loops and said nut. While I have shown the shade support connected through the medium of the screw 13 and nut 14, it will be obvious that the support may be riveted to the shade.

In practice when the shade is removed from the bulb the loops, 7, 8 stand substantially at right angles to the connecting portion 9, with the ends of the coils separated from the adjacent strand of wire, as clearly shown in Fig. 3. To apply the shade to the bulb the supporting loops are pushed on to the bulb causing the loops to spread or spring laterally, the bottom portion of the coils, as at 15, due to the resiliency of the

metal firmly clasping the bulb, and the ends of the wire coils having less inherent resiliency will readily adjust themselves to the shape of the bulb, with the result that the entire circular area of the loop will be in firm engagement with the lamp bulb, and will remain in firm engagement with the bulb no matter to what angle or inclination it may be adjusted to the longitudinal axis of the lamp, whether at an angle as shown in dotted lines in Fig. 1, or at right angles to the longitudinal axis of the lamp as shown in Fig. 2, and the shade when adjusted in such angular position may also be adjusted about the longitudinal axis of the lamp. To remove the shade it is only necessary to grasp the shade by the nut 14 and pull it off from the bulb.

Having thus described my invention, I claim:

1. The combination with a shade for incandescent lamps, of a support for said shade comprising a strand of material formed with a coil at each end, said strand being bent so that the coils are at an angle to the portion extending between and connecting the coils, and the support connected to the shade substantially centrally thereof by the portion extending between the coils, whereby the coils are adapted to engage a lamp at opposite sides to permit of the adjustment of the support and shade on the lamp to any angle relative to the longitudinal axis of the lamp and about the longitudinal axis of the lamp.

2. The combination with a shade for incandescent lamps, of a support therefor comprising a strand of wire the ends of which are bent at right angles and formed

into resilient loops to engage at opposite sides of the lamp, and the portion between the loops formed with a loop for the engagement of means to secure the support to the shade.

3. In a shade for incandescent lamps, the combination with a shade, of means to support the shade upon the bulb comprising a strand of wire formed with a spiral wound resilient coil at each end and bent to project at substantially right angles to the portion extending between and connecting the coils with the ends of the coils on the inner side, said coils adapted to engage opposite sides of the bulb at its greatest diameter and being of such size that portions of the bulb project through said coils and substantially all portions of the coils yieldingly engage with the bulb, and said support connected to the shade by the portion extending between the coils. 60

4. The combination with a shade for an incandescent lamp, of means to yieldingly support the shade upon the lamp bulb to permit of adjustment of the shade to any angle relative to the longitudinal axis of the lamp and about the longitudinal axis of the lamp, comprising a pair of connected spirally wound resilient wire coils, said coils being substantially at right angles to the connecting portion thereof, an eye formed in the connecting portion, a screw to pass through said eye and an opening in the shade, and a nut to have screw threaded connection with said screw outside of the shade 79
